J. H. HAMILTON,
LASTING MACHINE,
APPLICATION FILED JUNE 29, 1915.

1,319,278.

Patented Oct. 21, 1919.

INVENTOR.
John H. Hamilton
By his Attorney,
Nelson Howard

UNITED STATES PATENT OFFICE.

JOHN H. HAMILTON, OF BROCKTON, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

LASTING-MACHINE.

1,319,278.

Specification of Letters Patent. Patented Oct. 21, 1919.

Application filed June 29, 1915. Serial No. 36,951.

To all whom it may concern:

Be it known that I, JOHN H. HAMILTON, a citizen of the United States, residing at Brockton, in the county of Plymouth and 5 State of Massachusetts, have invented certain Improvements in Lasting-Machines, of which the following description, in connection with the accompanying drawings, is a specification, like reference characters on 10 the drawings indicating like parts in the several figures.

This invention relates to lasting machines and is herein shown as embodied in means for use in positioning the shoe stock for the 15 operation thereon of the gripper of a lasting and tacking machine which may be similar to that shown and described in United States Letters Patent No. 1,081,872, granted on application of E. A. Stiggins.

20 A feature of the invention consists in a novel organization comprising lasting means for engaging the margin of an upper, means for engaging the margin of the innersole to hold it against the last bottom, and means 25 for engaging the inner side of the upper materials and holding them for the action of the lasting means. A further feature of the invention consists in the combination with lasting means of stock positioning means 30 which engages the inner side of the upper materials and which is operated automatically and directly by the lasting means.

Another feature of the invention consists in 35 improved mechanism comprising the combination with lasting means of stock positioning means arranged to operate between the shoe upper and innersole at that lateral side of the lasting means where it is out of the way of the operation of laying over the 40 innersole the portion of upper acted upon by the lasting means. These and other features of the invention, which will be more fully understood from the following description and the accompanying drawings, 45 are herein shown as embodied in a mechanism in which the lasting means is a gripper and the stock positioning means includes a stock presenter for engaging the inner side of the upper materials and lifting the upper

50 up away from the innersole while the lower gripper jaw moves to gripping position under the upper, and an innersole feather edge holder located at one side of the gripper, the

presenter being operatively connected with the gripper to be moved thereby so as not 55 to interfere with the operative movements of the lasting means.

Figure 1 is a perspective view of the shoe engaging parts of a hand method type of gripper lasting and tacking machine 60 equipped with my invention and shows a shoe being operated upon;

Fig. 2 is a side elevation of the gripper and work guiding devices.

The gripper 2 comprises a lower jaw 4 65 and a relatively movable upper jaw 6, the respective faces of the jaws being toothed or roughened to enable them to hold the stock between them securely when they close. A shoe bottom rest 8 is arranged to engage the 70 innersole and is located to determine the vertical position of the shoe. A tack block 10 receives in a suitable tack pocket a tack from a separator 12 and is reciprocated over the edge of the shoe to wipe the upper into 75 lasted position after the grippers have tensioned it, the tack being then driven by a driver 14 through the upper and into the innersole. In making welt shoes the tack is left upstanding as shown in Fig. 1 to facilitate 80 subsequent removal. An edge rest 16 is arranged to assist in positioning the work horizontally. These parts of the illustrative machine may be substantially as in said patent. 85

The stock positioning means comprises a finger 20 secured to the work rest in downwardly and inwardly inclined position by screws 22 and slots which permit endwise adjustment of the finger. The inner end of 90 the finger is adapted to engage the margin of the innersole, being shown as engaging the feather of a welt innersole, and hold it down upon the last bottom so that the upper can be tightly lasted over the edge of the 95 innersole. This finger has its innersole engaging end located at one lateral side of the path of the tack block which reciprocates across the sole edge to the lasting point, so that said finger is not in the way of laying 100 the upper down and tacking it in lasted position. The inner end of the finger 20 pivotally supports the lower end of the stock presenter 24 which extends upwardly and outwardly relatively to the machine and has 105 sliding support in a bearing block 26 which

is pivotally mounted on the support for the lower gripper jaw. By reason of this connection with the gripper the gripper operates the stock presenter by oscillating it 5 about the pivotal connection at its lower end with the finger 20.

In the use of the invention, a shoe is presented to the machine as shown in the drawings. The finger 20 contacts with the margin 10 of the innersole at one side of the lasting point and presses it down upon the last bottom and holds it from being lifted or displaced in the lasting operation. The stock presenter 24 extends under the upper 15 and engages the inner side of the upper materials to hold them up for lower jaw 4 to get under them as the jaws move to upper seizing position. When the gripper is raised and is moved over the shoe bottom in 20 stretching and overdrawing the upper, sliding motion occurs between the pivoted block 26 and the presenter 24 and the presenter is moved downwardly so as not to interfere with the overdraw movement of the gripper, 25 but the lower end of the presenter remains continuously under the upper materials at one side of the lasting and tacking point. After the gripper has released the upper 30 and the fastening tack has been driven the shoe is fed along lengthwise by the operator for the next lasting operation. The lower ends of the members 20 and 24 remain, however, under the upper, the finger 20 holding the innersole margin down and the presenter 35 24 holding the upper materials up so that they will not be engaged by the jaw 4 as it descends and moves toward the edge of the shoe. The supporting points for the presenter in the finger 20 and the bearing 26 40 are so located and the presenter is so shaped that the presenter, which has a smooth upper engaging face, holds the upper above the toothed face of gripper jaw 4, as shown in Fig. 2, while the grippers move to upper 45 seizing position.

Having explained the nature of my invention, I claim as new and desire to secure by Letters Patent of the United States:

1. In a lasting machine, the combination 50 with a gripper having overdraw pulling movements and operating mechanism to return it to upper seizing position and close it after each pulling operation, of means operated by the gripper to engage the upper 55 materials and hold them where they will not be engaged by the lower jaw of the gripper during such return movement and until the gripper closes.

2. In a lasting machine, the combination 60 with a gripper and operating mechanism to return it to upper seizing position and close it after each pulling operation, of means connected at one end with the lower gripper jaw and having its other end continuously 65 under the upper materials and extending

in position to hold the upper materials above the lower jaw while the gripper returns to upper seizing position.

3. In a lasting machine, the combination with a gripper and operating mechanism to 70 return it to upper seizing position and close it after each pulling operation, of stock positioning means including a finger having an end located to extend between the innersole and the upper of a shoe presented to 75 the machine, and a coöperating device pivoted to said end of the finger and maintained relatively to the gripper in position to hold the upper out of engagement with the lower jaw of the gripper while the gripper is 80 moving to upper seizing position.

4. In a lasting machine, the combination with a gripper and operating mechanism to return it to upper seizing position and close it after each pulling operation, of a sole rest, 85 a reciprocating tack block, a finger secured to the rest and extending into position to engage the innersole of a shoe at one lateral side of the path of the tack block, and means pivoted to the finger and operated 90 to lift the upper up from the innersole into position to be seized by the gripper.

5. In a lasting machine, the combination with a gripper and operating mechanism to return it to upper seizing position and 95 close it after each pulling operation, of a sole rest, means extending beyond the work engaging face of the rest to engage the margin of the innersole and supported at one lateral side of the rest, and means for lifting 100 the upper out of the path of the lower jaw of the gripper as the gripper returns to upper seizing position.

6. In a lasting machine, the combination with a gripper and operating mechanism to 105 return it to upper seizing position and close it after each pulling operation, of a presenter having its lower end supported in position to be continuously between the upper and the innersole and always on the 110 same side of the gripper as the lasting proceeds, and means for raising the presenter in time relation to the gripper to assist the gripper in seizing the upper.

7. In a lasting machine, the combination 115 with a gripper and operating mechanism to return it to upper seizing position and close it after each pulling operation, of a presenter having its lower end supported in position to be continuously between the 120 upper and the innersole as the lasting proceeds and its upper portion connected with the gripper.

8. In a lasting machine, the combination with lasting means for engaging the margin 125 of an upper, of means directly connected with the lasting means for engaging the inner side of the upper materials and operated to lift them out of the way of the lasting means while the lasting means moves to 130

operative position relatively to the margin of the upper.

9. In a lasting machine, the combination with a gripper and operating means for the gripper, of a stock presenter arranged for engaging the inner side of upper materials and holding the upper up away from the innersole while the lower jaw of the gripper moves to gripping position under the upper, the presenter being operatively connected with the gripper.

10. In a lasting machine, the combination with a gripper and operating means for the gripper, of a stock presenter arranged for engaging the inner side of upper materials and operated to lift the upper up away from the innersole while the lower jaw of the gripper moves to gripping position under the upper, and a feather edge holder located 20 at one lateral side of the gripper.

11. In a lasting machine, the combination with a gripper and operating means for the gripper, of a stock presenter arranged for engaging the inner side of upper materials 25 and sliding connections between the gripper and the presenter for operating the pre-

senter to move the upper up away from the innersole while the lower jaw of the gripper moves to gripping position under the upper.

12. In a lasting machine, the combination 30 with lasting means, of stock positioning means arranged to operate between the shoe upper and innersole at that lateral side of the lasting means toward which the lasting is progressing and where it is out of the way 35 of laying over the innersole the portion of upper acted upon by the lasting means, and means to operate said positioning means to manipulate the stock and assist the lasting means in working the upper over the shoe 40 bottom.

13. In a lasting machine, the combination with lasting means, of stock positioning means which engages the inner side of the upper materials, and connections between 45 the stock positioning means and the lasting means for operating the stock positioning means to assist the lasting means in working the upper over the shoe bottom.

In testimony whereof I have signed my 50 name to this specification.

JOHN H. HAMILTON.
